CLAIM

The ornamental design for a needle-free disposable syringe as shown and described.

DESCRIPTION

FIG. 1 is an enlarged front elevation view of a needle-free disposable syringe showing my new design;

FIG. 2 is an enlarged rear elevation view of the needle-free disposable syringe as shown in FIG. 1;

FIG. 3 is a left-side elevation view of the needle-free disposable syringe as shown in FIG. 1;

FIG. 4 is a right-side elevation view of the needle-free disposable syringe as shown in FIG. 1;

FIG. 5 is a top plan view of the needle-free disposable syringe as shown in FIG. 1;

FIG. 6 is a bottom plan view of the needle-free disposable syringe as shown in FIG. 1; and,

FIG. 7 is a perspective view of the needle-free disposable syringe as shown in FIG. 1.

The broken lines in the drawings illustrate portions of the needle-free disposable syringe and form no part of the claimed design.

1 Claim, 4 Drawing Sheets
